(57) **CLAIM**

The ornamental design for a multi-purpose tool, as shown and described.

DESCRIPTION

FIG. 1 is a right side view of a multi-purpose tool showing our new design in a closed state;

FIG. 2 is a left side view thereof;

FIG. 3 is a front view thereof;

FIG. 4 is a rear view thereof;

FIG. 5 is an enlarged top view thereof;

FIG. 6 is an enlarged bottom view thereof;

FIG. 7 is a perspective view thereof;

FIG. 8 is another perspective view thereof;

FIG. 9 is another perspective view thereof;

FIG. 10 is a right side view of the multi-purpose tool of FIG. 1 in an alternate configuration, showing the shovel element in a partially open state;

FIG. 11 is a left side view thereof;

FIG. 12 is a front view thereof;

FIG. 13 is a rear view thereof;

FIG. 14 is an enlarged top view thereof;

FIG. 15 is an enlarged bottom view thereof;

FIG. 16 is a perspective view thereof;

FIG. 17 is another perspective view thereof;

FIG. 18 is another perspective view thereof;

FIG. 19 is a right side view of the multi-purpose tool of FIG. 1 in an alternate configuration, showing the shovel element in a fully open state;

FIG. 20 is a left side view thereof;

FIG. 21 is a front view thereof;

FIG. 22 is a rear view thereof;

FIG. 23 is an enlarged top view thereof;

FIG. 24 is an enlarged bottom view thereof;

FIG. 25 is a perspective view thereof;

FIG. 26 is another perspective view thereof;

FIG. 27 is another perspective view thereof;

FIG. 28 is another perspective view thereof;

FIG. 29 is a right side view of the multi-purpose tool of FIG. 1 in an alternate configuration, showing the axe element in open state;

FIG. 30 is a left side view thereof;

FIG. 31 is a front view thereof;

FIG. 32 is a rear view thereof;

FIG. 33 is an enlarged top view thereof;

FIG. 34 is an enlarged bottom view thereof;

FIG. 35 is a perspective view thereof;

FIG. 36 is another perspective view thereof;

FIG. 37 is another perspective view thereof;

(Continued)

FIG. 38 is a right side view of the saw element of the multi-purpose tool of FIG. 1, shown in a closed state and shown removed from the multi-purpose tool;
 FIG. 39 is a left side view thereof;
 FIG. 40 is a front view thereof;
 FIG. 41 is a rear view thereof;
 FIG. 42 is an enlarged top view thereof;
 FIG. 43 is an enlarged bottom view thereof;
 FIG. 44 is a perspective view thereof;
 FIG. 45 is another perspective view thereof;
 FIG. 46 is another perspective view thereof;
 FIG. 47 is another perspective view thereof; and,
 FIG. 48 is another perspective view thereof.
